ATTORNEY

UNITED STATES PATENT OFFICE.

STEFANES GABRIËLSE, OF ROTTERDAM, NETHERLANDS, ASSIGNOR TO HANDELS-
VENNOOTSCHAP FIRMA GABRIËLSE & CO., OF ROTTERDAM, NETHERLANDS.

STEAM-BOILER-CLEANING TOOL.

Application filed May 28, 1927, Serial No. 195,030, and in the Netherlands July 12, 1926.

This invention refers to a steam boiler cleaning tool particularly intended for scraping the parts of the boiler which are relatively near to one another and parallel to one another. Such parts or walls are formed on smoke boxes placed near to one another. Such walls are connected together by stay bolts. According to this invention, the scraper consists of a fork, one tine or 10 prong of which is provided with a roller, whilst the other prong is directed outwards and cut to a point like a knife edge. This tool is provided with a haft which can be lengthened or shortened as desired. Between 15 the two prongs of the fork an adjusting screw is provided with the aid of which the prongs can be screwed together.

When the scraper is adjusted between the two walls under treatment the prongs are 20 bent together by means of a screw, preferably a thumb screw, until the tool can be used between the walls under treatment. The screw is then released so that the prongs are applied on the wall like springs. Upon 25 the scraper being moved to and fro the point of one prong cleans the wall, whilst the other prong slides or rolls on the wall opposite. The scraper is then pulled up and down by hand. According to this invention 30 all the parts of the parallel walls can be easily reached and cleaned with the scraper. Leakage in the parts where the stay bolts are arranged is thereby prevented and the walls can be entirely and thoroughly cleaned, 35 so that the consumption of fuel in working the boiler is reduced. A further advantage is that the boiler can be cleaned in a much shorter time than was formerly the case and the cleaning can also be more thoroughly 40 executed.

The accompanying drawing illustrates an example of execution of the tool, according to this invention.

Fig. 1 is a side view of the tool, and

45 Fig. 2 is a side view of Fig. 1 seen from the right.

According to this invention the scraper consists essentially of two resilient prongs 1 and 2, of which prong 1 is provided with a laterally directed edge 3, whilst prong 2 is 50 provided with a roller 4. The two prongs are screwed fast in the holder 5, whilst a spring 6 is provided between the two prongs. Holes are bored through the two prongs, 55 whereby a screw 7 is adjusted by means of a thumb screw 8. A stem is connected with a holder 5 which can be extended or shortened in a simple way by approaching or removing the extension parts 9 which can be connected together by means of the sleeves 10. 60

In order to introduce the scraper between the walls under treatment, the thumb screw 8 is screwed on until the point 3 and the roller 4 can be introduced between the two walls, as shown in Fig. 1. Thereupon the 65 thumb screw 8 is released, so that the prongs are resiliently pressed against the wall-like springs. If the prongs themselves have sufficient resilient power the spring is superfluous. It is important that the stem can be 70 extended or shortened in order that the tool may be used in the narrow space available and all parts of the walls under treatment can be reached.

What I claim is:—

A steam boiler cleaning tool, comprising a holder having a recessed lower end, two resilient members having their inner ends secured in said recess, the outer ends of the members flaring outwardly, one of the members having its end formed into a knife edge and the other having a roller mounted therein, a spring having one end secured in the recess between the said members and forcing them apart, and means for drawing the 80 members toward each other against the action of the spring.

85 In testimony whereof, I affix my signature.

STEFANES GABRIËLSE.
